ATTORNEY

UNITED STATES PATENT OFFICE.

DONALD McDONALD, OF LOUISVILLE, KENTUCKY.

JAIL-BUCKET.

SPECIFICATION forming part of Letters Patent No. 437,614, dated September 30, 1890.

Application filed June 11, 1890. Serial No. 355,103. (No model.)

To all whom it may concern:

Be it known that I, DONALD McDONALD, of Louisville, in the county of Jefferson and State of Kentucky, have invented a new and 5 useful Improvement in Jail-Buckets, of which the following is a specification.

My invention is in the nature of an improved night-bucket for use in jails. The plan at present in use is to provide in each cell a 10 small closet with a ventilating-pipe leading out through the roof, in which closet the bucket is placed when not in use. This plan is open to several serious objections, the principal ones being that the closet necessarily 15 becomes foul and cannot be cleaned; also, that if damage is done to the closet it is difficult to repair it, and, further, that the bucket must be taken out of the closet for use.

It is the object of my invention to obviate 20 these objections and to provide a more cleanly and sanitary arrangement. To this end it consists mainly in providing a bucket with a tight cover, which bucket is provided with a hollow arm or spout which enters a ventilating-pipe and at the same time affords a 25 conduit for the exhalations of the bucket and a strong support for the same, as will be hereinafter fully described.

Figure 1 is a side elevation of my invention. 30 Fig. 2 is a rear elevation of the same, and Fig. 3 is a plan view.

In the drawings, A is the bucket, of iron or other material, having a tight-fitting lid F and a downwardly-projecting or hooked arm G near its upper edge. This arm acts as a support for the bucket, and is made hollow and communicates with the interior of the bucket. This hollow arm is entered into the open end of a T-coupling B, mounted upon 35 the top of a stand-pipe or column C, which is fastened to the floor of the jail in upright position. The T-coupling B is connected by a thimble H to an elbow I, connecting with the ventilating-pipe E, extending out through the

roof, or with the ventilating-flue which may 45 be already built.

The bucket is hung at a convenient height for use, and to steady it against movement it is provided near its lower end with a forked lug D, that embraces the stand-pipe or column C. This arrangement, it will be seen, provides a very substantial stand for the bucket, which cannot be broken and is not liable to become foul, and the bucket itself being detachable can be readily removed for 55 washing or be quickly replaced if broken or destroyed.

Having thus described my invention, what I claim as new is—

1. As a new article of manufacture, a jail- 60 bucket A, having a downwardly-curved tubular supporting and ventilating arm G on one side at its upper end, and a transverse curved steadyng lug or arm below and in vertical alignment with the said arm, substantially as 65 set forth.

2. The combination, with a jail-bucket having a downwardly curved hollow supporting-arm G, of the standard C, having an open upper end B, receiving the lower end of the arm 70 G, and provided with a lateral outlet and a ventilating-pipe communicating at its lower end with said lateral outlet, substantially as set forth.

3. The combination, with the standard C, 75 having an open upper end B, provided with a lateral outlet, and a ventilating-pipe communicating at its lower end therewith, of the bucket A, having a hollow downwardly-curved supporting-arm G at one side of its upper end, 80 fitting in said end B, and a curved transverse steadyng lug or arm D below and in vertical alignment with the arm G and resting against the standard C, substantially as set forth.

DONALD McDONALD.
